A. ROSENBERG

VESTED GARMENT

Filed July 25, 1924

Fig - 1

Albert Rosenberg INVENTOR.

UNITED STATES PATENT OFFICE.

ALBERT ROSENBERG, OF BALTIMORE, MARYLAND.

VESTED GARMENT.

Application filed July 25, 1924. Serial No. 728,171.

To all whom it may concern:

Be it known that I, ALBERT ROSENBERG, a citizen of the United States of America, and resident of Baltimore city, in the State of Maryland, whose post-office address is 1220 West Lanvale Street, have invented new and useful Improvements in Vested Garments, of which the following is a specification.

My invention relates to garments which 10 men and ladies use such as vested coats, i. e., coats which are worn over under clothing, and given the names of coats, jackets, over-coats, dresses, blouses, shirt-waists, etc. and may be applied to vests, shirts, etc., and my intention is to have this invention adaptable to all manufactured garments wherever it may be feasible to apply my vested garment construction, the objects of which are—

1st. to supply a new article of commerce, 20 2nd. to provide a vested garment. 3rd. to provide a coat with vestee which will have a dressy and nobby appearance. 4th. to supply a garment with an opening in which the ends of a commercial vestee 25 can be inserted to give the garment a finished appearance, while supplying the garment usable either with the vestee attached or ready to attach the said vestee.

5th. to supply a garment with means for 30 attaching a vestee with detachable means which will not interfere with the pressing of the said garments.

6th. to provide a double head button for use with vested garments.

35 7th. to provide a series of button holes to correspond with the holes in a vestee whereby a commercial vestee can be readily attached by any wearer.

Referring to the accompanying drawings,—

Fig. 1 is a coat showing the vestee attached.

Fig. 2 is a cross section of the coat at the lapel near the collar showing the double headed button with the button holes in section and also the section of the pocket opening for the end of the vestee.

Referring to the numerals, 1' is a coat looking at it from the inside of the garment, 50 and 2 is the doubled part of the cloth 1 on the inside of the coat which forms the lapel by folding back indicated by the dotted lines 2 and 7 and to which the collar indicated by 2' is attached. 3 is a pocket usually found in coat garments. 4 and 8 are the arm holes

in which the sleeves 5 and 9 are inserted and 6 is the seam of the sleeve.

The numerals 10 and 10 indicate the customary buttonholes in garments by which one side of the garment is fastened to the 60 opposite side carrying buttons for that purpose.

11 is my vestee, a standard article of commerce known by the name of vestee.

12—13—14—15—16—17—18 are seven 65 buttons inserted in buttonholes found in commercial vestees; and in the garment on the inside cloth only I provide complementary buttonholes 18' to match the vestee buttonholes 12—13—14—15—16—17—18.

19 and 20 are pocket openings in which the ends of the vestee 11 are inserted to hold them in place on the garment and to give the garment a finished appearance. 21 is the collar of the garment on the inside of 75 which the vestee 11 is buttoned.

The buttons 12—13—14—15—16—17—18 are detachable like cuff buttons and are to be removed when the garment is being pressed.

While it may be common practice to attach detachable collars to garments and vestees are common articles of commerce, yet heretofore no garment has been made with provision for inserting the ends of detachable vestees or detachable collar coverings 80 for the inside of coats or vests or other garments.

It will be seen that my double headed button can be used wherever buttons are now sewed on garments. By making buttonholes 90 where buttons now appear and using the double headed buttons, one end of which inserted in the buttonhole will form a detachable attached button for the garment whether it be for attaching suspenders or any other 95 device to a garment; and by making button holes to hold the double headed buttons, in place of the present vogue of sewing on buttons to fasten garments together it will obviate the annoyance occasioned by buttons 100 tearing off the garments and when lost the buttons may be easily replaced without sewing them on the garments.

It will be seen that the means for detachably securing the double-headed buttons, the 105 buttonholes in the garment may be made through both of the doubled portions of the cloth of the garment under the collar and under the lapel of the garment, or they may be made only in the inner pieces of the cloth 110

of the garment at the collar and at the lapel; and it will be seen that the lapel and the collar will hide the said buttonholes when made to include both of the said doubled 5 pieces of the cloth of the garment.

Claims:

1. A garment provided with a lapel and a collar and with a series of means for securing a vestee, said means secured to the inside 10 of the garment under the lapel and under the collar in alignment with the collar and the lapel, and slit places in the garment under the lapel for inserting the ends of a vestee patterned to align with the collar and the lapel.
2. A garment provided with a lapel and a collar and provided with a series of holes in the inside of the garment in alignment with the collar and the lapel for securing the 20 means whereby a vestee may be secured to the inside of the garment, the collar and lapel extending over the said series of holes.
3. A garment provided with a lapel and a collar, and with a series of holes in the inside cloth only of the garment in alignment with the collar and the lapel to register with the buttonholes in a vestee.
4. A garment provided with a collar and a lapel and with a series of buttonholes in 30 the inside of the garment in alignment with the lapel and the collar, and double-headed

detachable buttons, one head of each button engaging one of the said buttonholes, and the other head of each button being free to engage a registering buttonhole in a vestee. 35 the collar and lapel extending over the series of buttonholes.

5. A garment provided with a collar and a lapel, and with means for securing a vestee in alignment with the collar and the lapel, 40 and slit places in the inside of the garment crosswise of the lapel for inserting the ends of a vestee designed to align with the collar and the lapel.

6. A garment provided with a collar and a lapel, and provided with means for securing a vestee in alignment with the collar and the lapel; and means adjacent the lower 45 ends of the lapel having a free edge extending crosswise of the lapel, on the inside of 50 the garment, for securing the ends the vestee in alignment with the collar and the lapel.

7. A garment provided with a collar and a lapel, and provided with a vestee and means for securing the vestee in alignment with the collar and the lapel; and means adjacent the lower ends of the lapel having a 55 free edge extending across the vestee for securing the ends of the vestee in alignment with the collar and the lapel.

ALBERT ROSENBERG.
